Patented Jan. 11, 1910.

Application filed November 1, 1909. Serial No. 525,827. Term of patent 14 years.

To all whom it may concern:

Be it known that I, JOSEPH T. The figure is a front perspective view, showing the design of the article.

1 represents the base, serving as a receptacle.

2 represents an altar provided with a candelabrum 3, 4, upon each side of the altar, with a Sacred Heart 5 in the center

of the altar surrounded by finely executed scroll work.

6 represents a crucifix projecting above the altar, with the holy water font 7 at the base of the crucifix surmounted by a cherub 9, the whole combined to produce an ornamental effect of scroll work with intermingled religious symbols.

I claim:—

The ornamental design for an altar sick call outfit, as shown and described.
